UNITED STATES PATENT OFFICE.

ROBERT R. ROBBINS, OF FLORENCE, KENTUCKY.

WIRE-FENCE TIGHTENER.

1,304,806.

Specification of Letters Patent. Patented May 27, 1919.

Application filed February 28, 1918. Serial No. 219,635.

To all whom it may concern:

Be it known that I, ROBERT R. ROBBINS, a citizen of the United States, residing at Florence, in the county of Boone, State of Kentucky, have invented a new and useful 5 Wire-Fence Tightener; and I do hereby declare the following to be a full, clear, and exact description of the invention, such as will enable others skilled in the art to which 10 it appertains to make and use the same.

The present invention relates to certain new and useful improvements in wire stretchers, and has for its object to provide a device of this character which embodies 15 novel features of construction whereby the wires of an old or a new fence can be tightly stretched and secured to the fence posts without difficulty.

Further objects of the invention are to 20 provide a wire stretcher of this character which is comparatively simple and inexpensive in its construction, which can be readily mounted in position and placed in engagement with a fence wire, which can be manipulated by hand and caused to draw the wire 25 perfectly taut, and which can be easily carried from place to place.

With these and other objects in view, the 30 invention consists in certain novel combinations and arrangements of the parts as will more fully appear as the description proceeds, the novel features thereof being pointed out in the appended claim.

For a full understanding of the invention, 35 reference is to be had to the following description and accompanying drawings, in which:—

Figure 1 is a side elevation of a wire 40 stretcher constructed in accordance with the invention, showing the same as placed in operative position against the side of a fence post.

Fig. 2 is a top plan view thereof, with parts broken away and shown in section.

45 Corresponding and like parts are referred to in the following description and indicated in all the views of the drawings by the same reference characters.

Referring to the drawings, which illustrate 50 one embodiment of the invention, the numeral 1 designates an arched foot which is adapted to be applied to one side of a vertical fence post, such as that indicated at P. A threaded stem 2 projects from the arched 55 foot 1, being swiveled at one end to the mid-

dle of the arched foot, and provided at its outer end with a handle 3. A screw 4 is shown as passing loosely through the central portion of the arched foot and engaging the inner end of the threaded stem 2, thereby providing a swivel connection between the threaded stem and the foot. A bearing cup 5 may be applied to the back of the arched foot 1, and the end of the threaded stem 2 which is received within the bearing 60 cup may have a cap 6 fitted thereon, said members serving to provide an effective swivel joint between the arched foot and the threaded stem, and being readily renewable 65 in case of wear.

A cross head 7 is threaded upon the stem 2 and projects laterally upon opposite sides thereof, one side of the cross head being shown as provided with a handle 8 by means of which the cross head can be conveniently 70 held against rotation when turning the threaded stem to move the block outwardly and stretch the fence wire. A pair of flexible stretching cables, such as the chains 9, are suitably secured to opposite ends of the 75 cross head 7 by means of the staples 10. These chains are intended to extend upon opposite sides of the fence post, and are provided at corresponding intervals with hooks 11. Any selected pair of the hooks 11 80 can be brought into engagement with the fence wire F. These hooks 11 engage the fence wire on opposite sides of the post P, as indicated more clearly by Fig. 2, and when the threaded stem 2 is rotated to move the 85 cross head 7 away from the fence post, the fence wire is pulled tightly around the fence post in such a manner as to take up all slack 90 therein. While the fence wire is thus held taut a tie wire T of a suitable character may 95 be fitted around the back of the fence post and the ends thereof twisted around the fence wire F, as indicated at 12. The wire stretching implement can then be removed, and the fence wire will be held taut by the 100 tie wire T.

Having thus described the invention, what I claim as new and desire to secure by Letters Patent, is:—

A wire fence stretcher including an arched 105 foot adapted to fit against the back of a fence post, a threaded stem projecting from the back of the arched foot and having a swivel connection therewith, a handle for turning the threaded stem, a cross head fitted 110

upon the threaded stem and movable toward and away from the fence post by rotating the threaded stem, a handle projecting from the cross head to hold the same against rotation, a pair of chains formed of articulated links and connected to opposite ends of the cross head, and hook members applied to corresponding links of the side chains and projecting laterally therefrom, any selected 10 pair of hook members being adapted to be

brought into engagement with the fence wire.

In testimony whereof I have signed my name to this specification in the presence of two subscribing witnesses.

ROBERT R. ROBBINS.
